US0D1082768S

(12) **United States Design Patent** (10) **Patent No.:** **US D1,082,768 S**
(45) **Date of Patent:** **** Jul. 8, 2025**

(54) **ELECTRONIC DEVICE**

(71) **Applicant:** **Apple Inc.**, Cupertino, CA (US)

(72) **Inventors:** **Jody Akana**, Los Altos Hills, CA (US); **Molly Anderson**, San Francisco, CA (US); **Bartley K. Andre**, Los Gatos, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Clement Tissandier**, San Francisco, CA (US); **Eugene Antony Whang**, San Francisco, CA (US); **Rico Zörkendörfer**, San Francisco, CA (US)

(73) **Assignee:** **Apple Inc.**, Cupertino, CA (US)

(**) **Term:** **15 Years**

(21) **Appl. No.:** **29/959,493**

(22) **Filed:** **Aug. 26, 2024**

Related U.S. Application Data

(63) Continuation of application No. 29/842,330, filed on Jun. 13, 2022, now Pat. No. Des. 1,040,145, which is a continuation of application No. 29/616,272, filed on Sep. 5, 2017, now Pat. No. Des. 954,698, which is a

continuation of application No. 29/505,856, filed on Mar. 7, 2016, now Pat. No. Des. 800,716.

CLAIM

The ornamental design for an electronic device as shown
and described.

DESCRIPTION

FIG. 1 is a bottom front perspective view of an electronic
device showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the
electronic device that form no part of the claimed design.

The dot-dash broken lines in the figures show boundaries
that form no part of the claimed design.
